UNITED STATES PATENT OFFICE

MAX BARRINGER, OF NEW YORK, N. Y., ASSIGNOR TO ALBERT SONNENSCHEIN, OF NEW YORK, N. Y.

SASH-LOCK.

1,169,113.

Specification of Letters Patent. Patented Jan. 25, 1916.

Application filed September 3, 1915. Serial No. 48,788.

To all whom it may concern:

Be it known that I, MAX BARRINGER, a citizen of the United States, and resident of the Bronx, county of Bronx, city and State of New York, have invented certain new and useful Improvements in Sash-Locks, of which the following is a specification.

My invention relates more particularly to sash locks adapted to lock the two sashes together and simultaneously lock the sashes to the window casing or the window stops secured thereto.

The object of the device is to provide means for securing the lower sash in open position and simultaneously securing the upper sash so that it cannot be lowered or opened and neither sash can be displaced after having been locked in the desired position.

A further object is to provide a separable key or lever for operating the sash lock, which key or lever may be removed after the window has been locked with the sash in the desired position, thus providing a further means of safety in view of the fact that with the key removed an unauthorized person or one not provided with the necessary key could not unlock the window and move the sash.

In carrying out my invention I have shown one form of my device in the accompanying drawings, in which—

Figure 1 represents a perspective view of my device attached to a window and in locked position. Fig. 2 represents a plan view with the window casing and upper sash in section, the sash lock being in unlocked position. Fig. 3 is a plan view of the lock with the upper part of the casing and the key removed, the bolt members being in unlocked position. Fig. 4 is a view similar to that shown in Fig. 3 with bolt members in locking position. Fig. 5 is an end view 45 with the casing sectioned at 5—5 of Fig. 3.

Referring to the drawings 1 represents the casing of the device which is preferably provided with a tongue 2 extending laterally therefrom at the base of the casing 1 and adapted to serve as a means for fastening the lock to the top edge of the lower sash 3 by means of a screw 4, as shown in Fig. 2 of the drawings. The front of the casing has a depending lug or flange 5 through which a screw 6 is adapted to pass

and further serve to secure the device to the window sash as shown in Fig. 1 of the drawings.

Within the casing 1 bolt members 7 and 8 are slidably mounted preferably in alignment and adapted to slide in opposite directions. The bolt member 7 is provided with a laterally extending lug 9 which is provided with a roughened or toothed surface 10 adapted to engage the inner face of the front window stop 11 as indicated in Figs. 1 and 2 of the drawings. The bolt member 8 is provided with a similar lug 12 having a roughened or toothed surface 13 oppositely disposed with respect to the surface 10 and adapted to engage the middle window stop 14 when the bolts are in locking position. The bolt 8 is further provided with another lug or extension 15 which is roughened or provided with teeth 16 or similar devices adapted to engage the inner face of the upper sash 16 which is preferably provided with a metal strip or plate 17 secured thereto by suitable screws 18. The strip or plate 17 is provided with a plurality of teeth or engaging grooves adapted to coöperate with the end 15 of the bolt member 8 substantially as indicated in Figs. 1 and 2 of the drawings. It will be understood that the metal strip 17 may be of any desired length equal to or less than the length of the upper window sash.

The bolt members 7 and 8 preferably fit in the casing 1 so as to slide longitudinally thereof, the bolt member 7 being held in place by the walls of the casing. The side wall of the casing at 19 is cut away to form a slot through which the arm or lug 9 is adapted to project. The same wall of the casing 1 is cut away at 20 to form a slot through which the arm or lug 12 is adapted to project. The end of the casing at 21 is open so as to permit the serrated or toothed end 15 of the bolt 8 to project therethrough in order that it may coöperate with the strip 17 on the upper sash. To prevent the bolt 8 from sliding out of the casing it is slotted at 22 and a pin 23 passing therethrough is secured to the casing.

Between the inner ends of bolt members 7 and 8 I mount a double cam 24 preferably pivoted centrally between the ends of the bolt members, the pivots finding bearings in holes in the upper and lower plates of the casing. The cam member 24 is adapt-

ed to lie in the position indicated in Fig. 3 of the drawings when the bolt members 7 and 8 are in unlocked position and may be made to assume the position indicated in Fig. 4 of the drawings when the bolt members are in locked position. The upper pivotal member 25 of the double cam 24 is preferably squared or otherwise adapted to receive a finger lever or key member 26 by means of which the cam member may be suitably turned when it is desired to lock or unlock the sash. In order that the bolt members may be withdrawn from locking position I preferably provide the respective bolt members 7 and 8 with lugs 7^a and 8^a projecting longitudinally and adapted to overlap or extend beyond the respective ends of the cam 24. The lugs are preferably semi-circular on the inside so as to conform with the outer faces of the double cam 24 as indicated in Figs. 3 and 4 of the drawings. This construction enables the double cam to contact with the lugs 7^a and 8^a and simultaneously restore the bolt members 7 and 8 to the normal position indicated in Fig. 3. The key 26, as shown in Figs. 1 and 2, may be of any desired shape or design and, as previously indicated, may be removably attached to the squared shank or pivot 25 secured to the cam 24 and extending outside the casing of the device. Obviously other suitable key arrangement may be devised for operating the cam member 24.

The operation of the device is quite simple and it will be understood that the proportions of the various parts should be properly adjusted or designed to conform to the dimensions of the window to which it is to be attached. When attached it will be seen that when the device is in the position shown in Figs. 2 and 3 of the drawings the bolt members are in unlocked position and the engaging members 9 and 12 are out of engagement with the respective window stops 11 and 14 and the end 15 of the bolt 8 is out of engagement with the locking strip 17 of the upper sash. After the sashes have been adjusted to the desired position the key or lever 26 is turned to the position shown in Fig. 1 of the drawings and the sashes are locked together and to the window stops 11 and 14 by the engagement of the lugs 9 and 12 with the window stops and the toothed end 15 of the bolt 8 with strip 17 on the upper sash. The position of the cam 24 and the bolt members, when in locking position, is shown in Fig. 4 of the drawings.

Various modifications in the specific detail of the mechanism may be made without departing from the spirit and scope of the invention.

I claim:

1. A sash lock provided with a casing adapted to be fastened to the top edge of

the lower sash, a notched bar secured to the upper sash, locking members within said casing adapted to be forcibly thrust apart and lugs projecting from said members for engaging the casing and parting stops respectively of the window, one of said members being provided with means for engaging the notched bar on the upper sash whereby the sash may be locked together and to the window stops in any desired relative position. 70

2. A sash lock provided with a casing adapted to be fastened to the top edge of the lower sash, a notched bar secured to the upper sash, locking members slidably mounted within said casing and provided with lugs for engaging the casing and parting stops respectively of the window, one of said members having means for engaging the notched bar on the upper sash and a cam for simultaneously thrusting said members apart for locking the sash together and to the window stops in any desired relative position. 80

3. A sash lock provided with a casing adapted to be fastened to the top edge of the lower sash, a notched bar secured to the upper sash, locking members slidably mounted within said casing and provided with lugs for engaging the casing and parting stops respectively of the window, one of said members having means for engaging the notched bar on the upper sash, a cam for simultaneously thrusting said members apart for locking the sash together and to the window stops in any desired relative position, and manually operable means exterior of said casing for operating said cam. 90

4. In a sash lock the combination with a casing adapted to be secured to the top edge of the lower sash, of a notched bar secured to the upper sash, a pair of bolt members slidably mounted in said casing, lugs projecting laterally from said members provided with roughened faces adapted to engage the casing and parting stops respectively of the window when said slidable members are thrust apart, one of said members being provided with an engaging portion adapted to engage the notched bar on the upper sash simultaneously with the engagement of the window stops by said lugs and manually operable means for sliding said bolt members in opposite directions to lock and unlock the sash. 105

5. In a sash lock the combination with a casing adapted to be secured to the top edge of the lower sash, of a pair of members slidably longitudinally of said casing in opposite directions, lugs extending laterally of the respective members and adapted to engage the window stops when said members are thrust apart, one of said members being provided with a toothed face adapted to project through the casing, a toothed plate on the upper sash frame adapted to be en- 110
125
130

gaged by said toothed face of the sliding member, and manually operable cam means between the inner ends of said members for thrusting the latter apart and holding them in locking position.

6. In a sash lock the combination with a
casing adapted to be secured to the top edge
of the lower sash, of a pair of bolt members
slidably mounted therein to be moved in op-
10 posite directions, a double cam pivotally
mounted within said casing between and
adapted to coöperate with said bolts to
thrust and hold them apart, oppositely ex-
tending cam lugs on the inner ends of the
15 respective bolts adapted to coöperate with
said cam to retract said bolts and engaging
means carried by the respective bolts adapt-
ed when said bolts are thrust apart by said
cam to lock the sash together and to the
20 casing and parting stops of the window.

7. In a sash lock the combination with a

casing adapted to be secured to the top edge of the lower sash, of a pair of bolt members slidably mounted therein to be moved in opposite directions, a double cam pivotally mounted within said casing between and adapted to coöperate with said bolts to thrust them apart, oppositely extending cam lugs on the inner ends of the respective bolts adapted to coöperate with said cam to retract said bolts, a removable key or lever for operating said cam and toothed lugs projecting from the respective bolt members for engaging the window stops when said members are thrust apart, one of said members being provided with a toothed outer end for engagement with the upper sash whereby the sash may be locked together and to the window stops.

In testimony whereof I have hereunto set 40
my hand.

MAX BARRINGER.
